AUDIBLE SIGNAL DEVICE

Maurice E. Pipkin, New York, and Eli Judson Blake, Rochester, N. Y.; said Blake assignor to said Pipkin

Application January 28, 1928, Serial No. 250,238

5 Claims. (Cl. 177—7)

This invention relates to an improvement in audible signal devices and more particularly in horns of the diaphragm type, and the means for producing the vibration of the diaphragm.

5 Horns of the diaphragm type are old and well known, but prior to this invention, have included an actuator which contacts directly with and positively flexes the diaphragm, the operation of the actuator being controlled either mechanically or electrically.

10 The primary object of this invention is to provide an audible signal device including a diaphragm, which diaphragm is vibrated by electrical impulses set up and controlled by an electric circuit.

15 Another object of this invention is to produce an audible signal device capable of emitting more than one tone, the individual tones or components thereof being under the operator's control.

20 A further object of this invention is to produce an audible signal device including a howling system which comprises a self oscillating circuit or, in other words, a closed circuit that reacts upon itself and a diaphragm which responds to the 25 oscillations created by such circuit and produces a howl.

25 In attaining these and other objects we employ an electrical circuit which is tuned substantially to a natural frequency of the diaphragm and which includes a source of energy and an oscillator which varies the flow of energy in the tuned circuit in unison with the vibrations of the diaphragm and with the electrical oscillations of the circuit.

30 Other objects of this invention will be apparent from a consideration of the following specification and of the accompanying drawings which form a part thereof and in which

35 Fig. 1 is a plan view of one embodiment of this invention the casing and mouth piece being in cross section;

40 Fig. 2 is a side elevation of such embodiment the casing being in cross section;

45 Figs. 3 and 4 are views partly in cross section of a detail of such embodiment;

50 Figs. 5, 6, and 7 are diagrammatic views of various circuits that might be employed in carrying out this invention with a structure similar to the embodiment shown in Figs. 1 and 2;

55 Fig. 8 is a view in longitudinal section of another embodiment of this invention;

Figs. 9 and 10 are cross sectional views taken along the lines 9—9 and 10—10 of Fig. 8;

55 Fig. 11 is a view partly in section of a detail of such embodiment; and

Fig. 12 is a diagrammatic view of one type of circuit that might be employed in the embodiment shown in Fig. 8.

The embodiment of this invention selected for illustration in Figs. 1 to 4 inclusive of the foregoing drawing comprises a cupped casing 10 to the open end of which is secured a mouth piece 11. The inner end 12 of the casing is closed and the open end terminates in an outwardly extending flange 13 which corresponds in general 10 dimensions to a flange 14 formed on the mouth piece 11. Spanning the opening 15 of the casing 10 is a diaphragm 16 which is preferably clamped between the flange 13 of the casing and the flange 14 of the mouth piece by bolts or other suitable 15 means 17. Thus the diaphragm separates the casing from the mouth piece and also completely seals the casing 10.

Within the casing 10 are mounted a pair of electro-mechanical systems 20 and 21, the diaphragm 16 constituting an element of each. One of said systems emits the fundamental note of said diaphragm and the other emits one of the harmonic notes due to features which will be set forth hereinbelow. The elements and operation 25 of each system are similar so that only one need be described in detail, the same reference characters being applied to each.

Within the casing 10 are mounted a pair of electro-mechanical systems 20 and 21, the diaphragm 16 constituting an element of each. One of said systems emits the fundamental note of said diaphragm and the other emits one of the harmonic notes due to features which will be set forth hereinbelow. The elements and operation 25 of each system are similar so that only one need be described in detail, the same reference characters being applied to each.

Each system includes a permanent magnet 22 supported within the casing in a predetermined 30 position by any suitable means, as, for example, that described hereinbelow.

Secured in any suitable manner to the ends of the arms 25 of the magnet 22 are blocks 26 of soft iron which function as pole pieces for 35 the magnet 22 and project beyond the ends thereof. Rigidly attached to the magnet 22 by feet 27 is a granular carbon transmitter button 28 of a type well known in the telephone art. The internal construction of this transmitter button 40 is no part of the present invention and hence is not here illustrated and will not be described in detail. It is sufficient for the present purpose to state that it has the characteristics of varying its electrical resistance in response to small 45 variations of pressure applied at the pressure head 29. An armature 30 is rigidly connected to the pressure head 29 of the transmitter button 28 and extends across the inner ends of the pole pieces 26. The armature is held away from the 50 pole pieces 26 by a spring 31 which thus places a normal pressure upon the head 29 of the button 28. The mass and resiliency of each armature 30 and its connections are so proportioned that its natural frequency of vibration is the 55

same as a natural frequency of the diaphragm 16. Across the arms 25 of the magnet 22 is mounted a fixed condenser 32 secured in place by means of screws 33.

5 Thus two paths are provided in the system through which the magnetic flux will flow between the pole pieces 26, one through the diaphragm 16 and the other through the armature 30. Associated with the armature 30 is a regenerative member, in the present embodiment the transmitter button 28. As previously pointed out one feature of this invention is to provide means for varying the magnetic flux in both paths. One such means will be described below, such description being merely illustrative and not limitative.

10 The magnetic flux through the body of the magnet 22 is held substantially constant by the nature of the permanent magnet. Wound around each pole piece 26 is a coil 35 by which the flow 20 of the flux through the two alternate paths is influenced and varied. Hence through each path there is a constant component of magnetization due to the permanent nature of the magnet 22 and a variable component due to the coils 35.

15 Figs. 1 to 4 inclusive disclose the systems 20 and 21 secured in the casing 10 by means of a flanged cup 40, the flange 41 thereof extending between the flanges 13 and 14 and being clamped behind the diaphragm 16 by the bolts 17. Near 20 the center of the cup 40 are formed a pair of parallel slots 42, through which the pole pieces 26 extend. The pole pieces are wider than the slots 42 and are provided with notches 43 at the ends of the arms 25, which receive the edges 44 of the 35 slots 42. The cup 40 and the pole pieces 26 when placed in the slots 42 and secured to the arms 25 will thus support the magnets 22 and the other elements of the systems 20, 21. The coils 35 are separated from the bottom of the cup 40 by suitable insulation 45. Suitable openings through the bottom of the cup 40 are provided to permit the electrical connection of the coils 35 with the other elements of the systems.

20 In the following description of the electrical connections and operation attention is directed to Fig. 5 the electrical connections having been omitted from Figs. 1 and 2 for the purpose of clarity. In that figure to the various elements diagrammatically shown are applied the reference 45 characters previously employed.

25 The coils 35 are in series, the outer ends being connected by a lead 36 and the inner ends of the coils being connected by leads 37 and 38 to the fixed condenser 32, (see Fig. 5). The condenser 32 is of such capacity that coils 35 and their connections form a tuned circuit—the frequency of which is determined by the condenser 32 to be the same as the pitch of the diaphragm 16. Thus the tuned circuit and diaphragm 16 constitute 30 an electromechanical system predisposed to oscillate at a natural frequency of the circuit and the diaphragm.

35 Current is supplied to the tuned circuit from a suitable source of energy such as a battery 50 one pole of which is directly connected to the lead 38 of the tuned circuit by a lead 51. The other pole of the battery is connected to the armature 30 by a lead 52 which includes any type of make 40 and break switch indicated on Fig. 5 by the numeral 53. The base of the button 28 is connected to the tuned circuit by a lead 54 joining the lead 37. The lead 52 is here shown connected to the negative pole of the battery 50 and the operation 45 of the system 20 will be so described. Upon clos-

ing the switch 53 direct current will flow from the battery 50 through the coils 35 and return through the armature 30 and the transmitter button 28 to the battery. The current flowing through the coils 35 weakens the attraction 5 between pole pieces 26 and diaphragm 16 and strengthens the attraction between the pole pieces 26 and the armature 30. The pressure of the armature against the transmitter button 28 is thereby lowered with a consequent increase of 10 resistance in the transmitter button and a resulting diminution of current in the circuit. The attraction between the pole pieces 26 and the armature 30 is therefore weakened with the result that the spring 31 is free to exert increased pressure 15 upon the transmitter button, decreasing the resistance of the latter and causing the current to increase again, whereupon the same cycle is repeated as long as the switch remains closed. These variations of attraction, pressure and resistance 20 modulate the current flowing in the circuit at a frequency determined by the resonant frequencies of the armature 30 and the electrical circuit. As previously stated these elements are resonant at the same frequency as diaphragm 16. 25

A portion of the pulsating current flows through the condenser 32 in the tuned circuit, thus maintaining oscillations at the frequency determined by the condenser 32 which frequency, as previously stated, is the same as that at which 30 the diaphragm 16 and armature 30 are predisposed to oscillate. The diaphragm 16 will thus be actively vibrated and emit a howl or powerful note into the mouth piece 11. The pitch of the howl or note is determined by the natural frequency 35 of the tuned circuit through the condenser 32, the diaphragm 16 and the armature 30 and its spring support 31.

The electro-mechanical system 21, while similar in structure, operation and function to the 40 system 20, differs therefrom in that the tuned circuit comprising the coils 35 and the condenser 32 is tuned not to the fundamental frequency of the diaphragm 16 but to some other frequency which may be harmonic thereto, and the armature 30 is also predisposed to oscillate at such frequency. Furthermore, the poles 26 are preferably presented to an anti-nodal point of the diaphragm 16 when vibrating at such other frequency. Hence upon closing the switch 53 the 50 diaphragm will emit a howl or note in the same manner that has been described, but at another tone, which may be any pitch harmonic to the note created by the system 20. Both switches may be closed simultaneously thus causing both 55 notes to be emitted by the device and produce a chime effect.

Fig. 6 shows diagrammatically another embodiment of the invention in which a vacuum tube 60 takes the place of the transmitter button and acts regeneratively to maintain oscillations of the electric circuit and hence vibrations of the diaphragm. In this embodiment an "A" battery 61 is shown for heating the filament of the vacuum tube 60, and a transformer 62 is shown for 65 coupling the grid of the vacuum tube to the output circuit in a manner well known in the art.

Fig. 7 shows another circuit which could be used and which differs from the circuits shown in Figs. 5 and 6 in that battery 50 and the transmitter button 28 are connected in series with the oscillating circuit instead of bridging the condenser. A resistor 70 is provided to by-pass the direct current component of current in the circuit around the condenser 32. In this circuit the 75

total oscillating current passes through the input elements, viz. the battery 50 and the regenerative element 28. The current required from this source is therefore relatively large; but the voltage supplied by the input elements at resonance is only that required to overcome the resistance of the circuit; whereas in Figs. 5 and 6 the current is supplied at the total voltage across condenser 32.

10 It should be observed that in every one of these embodiments we have an electro-mechanical system predisposed to oscillate at a particular frequency and including a regenerative member. The regenerative member is in two cases a transmitter button and in the other case a vacuum tube upon which the oscillations of the system react to cause increased variations of energy supplied to the system at the same frequency; but other regenerative members could be substituted for those here shown without impairing the operation of the system.

15 The coils 35 cooperating with the regenerative member function as an amplifier, i. e., they act to deliver increased pulsating energy to the system in response to the current in the system itself functioning regeneratively as the input circuit to the amplifier.

20 Figs. 8-12 inclusive disclose a more compact embodiment of this invention which however functions in the manner previously described.

25 This embodiment comprises a cupped iron casing 100 to the open end of which a mouth piece 101 is secured by crimping over the edge of the casing as shown or in any suitable manner. In 30 the casing 100 are mounted two cups 102, 103 spaced apart by two pillars 104 and retained between the back wall of the casing 100 and the mouth piece 101. The inner cup 102 faces the closed end of the casing 100 and is provided with 35 apertures 105, 106 which receive thimbles 107, 108 for a purpose to be described later. The outer cup 103 is provided with a pair of parallel slots 109, 110 and a pair of bushed openings 111, 112 adapted to accommodate wires leading from 40 the interior of the cup 103 to the space behind it. Through the slots 109, 110 extend two pole pieces 113, 114 having heads 115, 116 of somewhat greater width than the slots to form shoulders which abut against the bottom of the cup 45 103 as shown in detail in Fig. 11. The inner portions of the pole pieces 113, 114 are secured to the poles 117, 118 of a single arcuate magnet 119 by means of screws 120. An arched resilient plate 203 interposed between the ends of the magnet 119 and the under side of the cup 103 serves 50 to draw the pole pieces 113, 114 inwardly and hold the overhanging shoulders thereof firmly against the bottom of the cup 103. An iron block 122 attached to the magnet 119 near its center 55 serves as a magnetic bridge connecting the neutral zone of the magnet to the iron casing 100.

60 Each of the heads 115, 116 supports a coil 124 connected to other parts of the device as described hereafter by wires passing through the bushed openings 111 and 112 but are omitted in Fig. 8 for the sake of clearness.

65 Mounted upon the outer face of the cup 102 are transmitter buttons 130, 131. These buttons are of a well known type each comprising a chamber 132 filled with granular carbon particles 133 and sealed by a flexible film 134 held over the chamber 132 by a flanged ring 135 threaded externally upon the outer wall of the chamber. Carried by the film 134 in contact with the carbon particles 133 is a plate 136 which is supported 70

on the outer face of the film 134. A second plate 139 is mounted at the base of the chamber 132 also in contact with the carbon particles 133. A pin 140 projecting from the base of the chamber 132 and here indicated as integral therewith extends through the thimbled aperture 105 or 106. The buttons 130, 131 are thus mounted upon the cup 102 and are secured in place by means of set screws 141, 142 which pass through the thimbles 107, 108 and bear upon the pins 140. 10

15 An armature 143 is rigidly supported at one end upon an insulating block 144 which is secured to the outer face of the cup 102 by a screw 145 and to the armature 143 by a screw 146. The armature 143 extends between the transmitter button 130 and the inner end of the pole piece 113. The end of the armature 143 near the block 144 is provided with a flange 147 preferably arcuate as shown in Fig. 10 and separated from the wall of the casing 100 by suitable insulation 20 148. The other end of the armature 143 is provided with a weight 149 which extends between the inner ends of the pole pieces 113, 114. The armature 143 is of steel or other elastic magnetic material rigidly attached near one end to the block 144. The free end is capable of movements of small extent by flexing and a neck 150 of reduced thickness may be provided near the point of support to increase the flexibility of the armature. Near its free end the armature is connected 30 to the pressure head 138, on the screw 137 which projects from the pressure head, by means of nuts 151.

35 A second armature 152 is mounted upon the cup 102 and extends between the transmitter button 131 and the inner end of the pole piece 114. The armature 152 is fixed to an insulating block 153 carried by the cup 102 by means of a screw 154 and terminates in an arcuate flange 155 which extends between the block 153 and the wall 40 of the casing 100 being separated from the latter by suitable insulation 156. The armature 152 like the armature 143 is attached to the screw 137 of the pressure head 138 of the transmitter button 131 by nuts 157. The pins 140 form electric 45 connections from either transmitter button to the "ground" on the framework of the instrument, while the screws 146 and 154 by which the armatures 143 and 152 are attached to the insulating blocks 144, 153 act as insulated terminals. 50

Within the cup 103 are mounted two induction coils 158, 159 for a purpose to be described hereafter and attached to the rear face of magnet 119 by suitable clamps not shown in the drawings, are two condensers 160 and 161. 55

60 In the closed end wall of the casing 100 are provided openings 162, 163 within which are secured terminals 164, 165 suitably insulated from the casing 100. A screw 166 is also threaded into a button 167 which is riveted into the wall of the 65 casing and in electrical contact therewith. The grounded screw 166 and the insulated terminals 164, 165 accommodate the external connections to the device.

65 Extending across the mouth of the casing 100 is a diaphragm 170 preferably of iron held by a ring 171 against the outer edge 172 of the cup 103. A weight 173 may be secured at the center of the diaphragm.

70 The mouth piece 101 may be flanged at its inner end as at 174 and closed at its outer end by a rubber disc 175 protected by wire mesh 176. The device may be supported upon a bracket 180 secured to the casing 100 by suitable means such as rivets 181. 75

The neutral zone of the magnet 119 communicates with the edge of the diaphragm 170 through the block 122 and the casing 100. Thus two independent paths of magnetism are provided. One path extends from the block 122 through the magnet 119, the pole 117, the pole piece 113, the air gap between the head 115 of the pole piece 113, the diaphragm 170, and the casing 100 back to the block 122. The other path extends from the block 122 to the opposite pole 118, pole piece 114, the air gap, diaphragm and back through the casing 100 to the block 122.

Moreover the armature 143 with the short gap through the insulation 148 and the casing 100 constitutes a magnetic path between the inner end of the pole piece 113 and the neutral zone of the magnet 119 similar to the path just described formed by the diaphragm 170 and the casing 100 from the head 115 of the same pole piece 113. In the same way the armature 152 and the casing 100 constitute a magnetic path from the inner end of the pole piece 114 to the neutral zone.

Therefore the poles 117, 118 of the magnet 119 act independently and take the place of the two horseshoe magnets 22 in the embodiment previously described.

For the sake of clearness the electrical connections of the parts which have been described are omitted in Figs. 8, 9, and 10 and are shown diagrammatically in Fig. 12. Referring to the latter it may be seen that when a switch 200 is closed current will flow from a battery 201 through the primary winding of the induction coil 158, the armature 143, the transmitter button 130 and the grounded terminal 166 to the opposite terminal of the battery. When the armature 143 vibrates causing fluctuating pressure upon the transmitter button 130 the current in the circuit will fluctuate and an alternating voltage will be induced in the secondary winding of the induction coil 158 causing current to flow in the tuned closed circuit through the secondary winding, the condenser 160 and the coil 124. The resonant frequency of the tuned circuit is an inverse function of the capacitance of the condenser 160 and the inductance of the windings included in the closed circuit. When a low frequency is desired the inductance required with a given condenser 50 is relatively high and the resistance of the coil 124 will ordinarily be high also. When the coil and condenser are connected directly to the battery a high battery voltage is required, corresponding with the high resistance of the coil 124. The function of the induction coil 158 is to step up the alternating component of voltage to a value suitable for a coil of high inductance and resistance when the primary circuit is operated from a source of low voltage and high current 60 capacity.

A switch 202 controls the corresponding parts 159, 152, 131, 161, and 124 in the lower portion of the diagram which constitute primary and secondary circuits identical with those which have 65 been described, but adapted for operation at a different frequency which may be one harmonic to the frequency of the upper circuits.

The weights 173 and 149 which are shown in Fig. 8 attached respectively to the diaphragm 170 and the armature 143 are for the purpose of loading these parts for a lower natural frequency of vibration than they would otherwise have.

As previously pointed out in connection with the first embodiment the transmitter button will 75 function as a regenerative member to set up

oscillations and cause a vibration of the diaphragm 170 which will emit a howl into the mouth piece 101.

The transmitter button 130, armature 143, coil 124 on the pole piece 113 and their connections 5 form an electro-mechanical system tuned to the fundamental frequency of the diaphragm 170, the mass and resiliency of the armature 143 and its connections being so proportioned that its natural frequency of vibration is the same as the 10 fundamental frequency of the diaphragm 170.

In the same respect the button 131, armature 152, coil 124 on the pole piece 114 and their connections form an electro-mechanical system 15 tuned to another frequency which may be one harmonic to the fundamental frequency of the diaphragm 170, the mass and resiliency of the armature 152 and its connections being so proportioned that its natural frequency of vibration is the same as that of the system as a whole. 20

While certain embodiments have been shown and described, we are not limited thereto since it is obvious that other embodiments of this invention could be made without departing from the spirit and scope of this invention as set forth 25 in the following claims.

Having thus set forth our invention, what we claim is new and for which we desire protection by Letters Patent is:

1. In an audible signal device a permanent 30 magnet, a pole piece extending from a pole thereof and acting upon a diaphragm through one air gap and upon a vibrating armature through a second air gap, a coil surrounding said pole piece so disposed that current acting therein to 35 increase the permanent flux of said magnet at one air gap diminishes the permanent flux at the other air gap, and an electric circuit including said coil, a source of direct current and a modulator actuated by the vibrating armature, and 40 acting to diminish the current in the electric circuit as the armature is attracted to the pole piece and thereby to maintain current oscillations through the coil and to sustain vibration of said 45 vibrating armature and said diaphragm.

2. In an audible signal device a permanent magnet, a pole piece extending from a pole thereof and acting through one air gap upon a diaphragm resonant at a certain frequency and 50 through a second air gap upon a vibrating armature resonant at the same frequency, a coil surrounding said pole piece so disposed that current acting therein to increase the permanent flux of said magnet at one air gap diminishes the permanent flux at the other air gap, and an 55 electric circuit including said coil, a source of direct current and a modulator actuated by said vibrating armature, and acting to diminish the current in the electric circuit as the armature is attracted to the pole piece and thereby to maintain current oscillations through said coil and to sustain vibration of said vibrating armature and 60 said diaphragm.

3. An audible signal device comprising a casing, cups in said casing, a permanent magnet in 65 said casing between said cups, pole pieces fixed upon the poles of said magnet and projecting through slots in one of said cups, coils on the projecting ends of said pole pieces, a diaphragm adjacent to the outer ends of both pole pieces, 70 two armatures adjacent to the inner ends of said pole pieces respectively, two microphones actuated by said armatures respectively and fixed to the other cup, and oscillating electric circuits supplied by a source of power including said coils 75

and said microphone, these elements being so disposed that oscillating currents in the electric circuits on the one hand cause the diaphragm to vibrate and to emit sounds corresponding to the variation of electromagnetic attraction between the pole pieces and the diaphragm, and, on the other hand actuate the microphone in accordance with the variation of electromagnetic attraction between the pole pieces and the armature, thereby sustaining the electric oscillations in the circuit.

4. An audible signal device comprising a sound projector and a microphone mechanically resonant to the same frequency, an oscillating circuit also resonant to said frequency electromagnetically coupled to said projector and said microphone and including said microphone and a source of direct current, said microphone maintaining electric oscillations in said circuit while the sound

projector and its electromagnetic coupling translate said oscillations into sound waves.

5. An audible signal device comprising a cupped casing, a diaphragm extending across the mouth of said casing, a permanent magnet, an armature and a modulator actuated by said armature in said casing, a pole piece secured to one pole of said magnet, cooperating at one end with said diaphragm and at the other end with said armature, a coil surrounding said pole piece and an electric circuit including said coil, said modulator, and a source of direct current, said circuit being resonant at a natural frequency of the diaphragm and acting regeneratively to maintain oscillating electric current through the coil and thereby to cause vibrations of said diaphragm.
